NONGLARE LIGHTING EQUIPMENT

Conrad R. Buchet, Los Angeles, Calif., assignor to
Darrell Marsden Dowding, Los Angeles, Calif.

Application July 26, 1941, Serial No. 404,181

3. Claims. (Cl. 240—41.3)

This invention relates to non-glare lighting equipment.

The general object of the invention is to provide an improved non-glare lighting device of a portable or fixed nature in which the parts are so constructed that a maximum of light and a minimum of glare is present when the device is used.

Another object of the invention is to provide a lighting device wherein a filament and a reflector member are employed and wherein light passes from the filament through a lens member which causes the light to converge to spaced locations and wherein adjacent to the place of convergence a second lens member is mounted which includes parallel alternate opaque and transparent portions with the light passing through the transparent portions.

A more specific object of the invention is to provide a lighting device particularly adapted for lighting an airport wherein novel means is provided for preventing glare from the light.

A further object of the invention is a novel combined diffusion and light directing member.

Another object of the invention is a novel lens member including alternate spaced parallel opaque and transparent portions.

Another object of the invention is to provide a lighting device including a novel pivotally mounted light member and including novel means for moving the member.

Other objects and advantages of the invention will be apparent from the following description taken in connection with the accompanying drawings, wherein:

Fig. 1 is a fragmentary, sectional, side elevation of a lighting device embodying the features of my invention;

Fig. 2 is a front elevation on a reduced scale;

Fig. 3 is a side elevation view, partly diagrammatic on a reduced scale; and

Fig. 4 is a fragmentary sectional side elevation of a modification of my invention.

Referring to the drawings by reference characters I have shown my invention as embodied in a lighting device which is indicated generally at 10. As shown, the device is mounted on a base 11 which includes an upwardly extending portion 12 thereon. Mounted on the base 11 I show a pair of legs 13 each of which includes a foot portion 14 secured as by rivets 15 to the base 11. At their upper ends the legs 13 are welded as at 16 to the exterior of a housing 17. As shown the interior of the housing at the rear is concave and preferably includes an interior reflecting surface 18 at the rear thereof and a non-reflecting interior surface 19 at the forward portion thereof.

The housing includes an aperture 20 through which the socket 21 of a lamp 22 extends. The

lamp includes a rectilinear, elongated, filament 22 which is preferably horizontally disposed. The filament 22 is shown as connected by leads 23 and 24 with a source of current 25 and with a switch 26, the construction being such that when the switch 26 is closed the filament 22 is lighted.

Mounted within the housing 17 I show a light transmitting assembly which includes a casing 27 which is preferably cylindrical and is provided with an annular collar 28 at the inner end thereof. The collar 28 includes a shoulder 29. Arranged in the collar 28 and engaging the shoulder 29 I show a light transmitting element 30. A sleeve 31 engages the inner face of the element 30 adjacent the outer periphery thereof. The sleeve 31 includes out-struck bosses 32 which space it from the casing 27. At the end of the casing 27 remote from the element 30 I show a second light transmitting element and is also engaged by a split retaining ring 34 which seats in a bead 35 in the casing 27.

The forward end of the housing 17 includes flange 36 against which a transparent closure member 37 is held by a split ring 38 arranged in a bead 39 in the flange 36.

As shown in Figs. 1, 2, and 3 the casing 27 is provided with diametrically opposed outwardly directed pins 40 which are welded in place as at 41. The pins 40 extend outwardly through circular apertures 42 in the housing 17. To the outer ends of each pin 40 I secure a depending arm 43. The lower ends of the arms 43 are connected by a transversely extending rod 44 which is pivotally connected intermediate its length as at 45 to one end of a link 46. The other end of the link 46 is pivotally connected to an arm 47 secured to a movable end plate 48 of a bellows 49. The fixed end of the bellows 49 is secured to the upwardly extending portion 12 of the base 11.

One end of a guide rod 50 is secured as by welding to the upwardly extending portion 12 at each side of the bellows 49 and slidably extends through an aperture 50' in the movable plate 48. The other end of each rod 50 is secured to an upturned tongue 12' extending from the base 11. About each guide rod 50 I mount a compression spring 51. One end of each compression spring 51 engages the upturned tongue 12' and the other end of each spring engages the movable plate 48.

As shown in Fig. 3 the upwardly extending portion 12 includes an internally threaded boss 52 thereon in which is secured a conduit 53 which communicates with the interior of the bellows. The other end of the conduit 53 communicates with the interior of a liquid storage tank 54. The liquid in the tank is maintained under pressure by compressed air supplied

through an air intake 55 at the upper end thereof which connects to an air pump 56. The conduit 53 includes a control valve 57 intermediate the length thereof. The valve 57 may be conveniently disposed near the switch 29.

Thus it may be seen that as the valve 57 is opened, the bellows will expand thus pushing forward the link 46 and thereby rotating the arms 43 and through the medium of pins 40 rotating the light transmitting assembly within the housing 17. When the valve 57 is operated to reduce the pressure the bellows will contract by means of compression springs 58 thus rotating the light transmitting assembly in the opposite direction.

The outer portions of the rear face of the light transmitting element 30 includes a plurality of light diffusing depressions 58. The central portion of the rear face of element 30 is preferably planar as at 59. The front or inner face of the element 30 includes a plurality of sets of horizontally disposed light condensing, rib forming lens surfaces 60. The ribs of the upper set is of intermediate width, the second set is narrower, the third set of the same width as the first set and the lower set has wider ribs than any of the other sets.

The lens surfaces, as shown in Fig. 1, are truncated as at 61 leaving only the upper half of each lens surface thus directing light horizontally transmitted through element 30 only in a horizontal or downward direction. The second light transmitting element 33 on each face thereof includes horizontally disposed raised clear glass portions 62 which are each of a width substantially equal to the width of and disposed in the path of the refracted light waves which were horizontally transmitted through the element 30 (see Fig. 1). The remaining depressed portions 63 of each face of the element 33 is ground and thus rendered opaque to prevent light passing therethrough.

Thus it may be seen that the light passing through elements 30 and 33 is directed only in a horizontal or downward path when the light transmitting assembly is in a vertical position as shown in Fig. 1.

In Fig. 4 I show a modification of my invention which is substantially similar to that shown in Figs. 1, 2, and 3 inclusive with the exception of the rear face of the front light transmitting element. As shown, within the sleeve 31' I arrange a series of horizontally extending T-shaped bars 64 which extend across the front thereof and are secured as by adhesive to the rear face of front element 33' in alignment with the depressed, ground-glass portions 65 of the front face of element 33'. The T-bars 64 are of non-light-transmitting material such as metal, thus obstructing the passage of any light incidental thereto.

Thus it may be seen that this construction also permits the transmission of light only in a horizontally or downwardly directed path when the light transmitting assembly is in a vertical position as shown in Fig. 4.

From the foregoing it will be apparent that I have invented a novel non-glare lighting equipment which can be economically manufactured and which is highly efficient for the intended purpose.

Having thus described my invention, I claim:

1. In a lighting device, a base, a leg on said base, a housing secured to said leg, a light transmitting member within said housing, said member including a casing, said casing having an outwardly directed pin thereon, said housing having an aperture, said pin extending through said aperture, a depending arm mounted on said pin, a link, means connecting the lower portion of said arm to said link, a bellows mounted on said base, said bellows having an end plate thereon, said link being secured to said end plate, a guide rod on said base, a tongue on said base and engaging said guide rod, spring means normally urging said bellows end plate in one direction, a boss on said upwardly extending portion and a conduit communicating with the interior of said bellows.

2. In a lighting device, a base, a pair of legs secured to said base, said legs being spaced apart, a housing secured to said legs, a light transmitting member within said housing, said member including a casing, said casing having aligned outwardly directed pins thereon, said housing having apertures, said pins extending through said apertures, a depending arm mounted on each of said pins, a rod connecting the lower portion of each of said arms, a link having one end pivotally connected to said rod, a bellows mounted on said base, said bellows having an end plate thereon, the other end of said link being secured to said end plate, a guide rod on said base and coaxial with said bellows, a tongue on said base and engaging said guide rod, a spring on said guide rod, said spring having one end engaging said tongue and the other end engaging said bellows end plate, a boss on said upwardly extending portion and a conduit communicating with the interior of said bellows.

3. In a lighting device, a base having an upwardly extending portion at one end thereof, a pair of legs each having a foot portion secured to said base, said legs being spaced apart, a housing secured to said legs and extending above the legs, said housing having an arcuate rear portion and a cylindrical forward portion, a light transmitting member within said housing, said member including a cylindrical casing, said casing having aligned outwardly directed pins thereon, said housing having apertures, said pins extending through said apertures, a depending arm mounted on each of said pins, a rod connecting the lower portion of each of said arms, a link having one end pivotally connected to said rod, a bellows mounted on said upwardly extending portion of said base, said bellows having an end plate remote from said upwardly extending portion, the other end of said link being secured to said end plate, a guide rod on said upwardly extending portion and disposed coaxial with said bellows, a tongue on said base and engaging said guide rod, a spring on said guide rod, said spring having one end engaging said tongue and the other end engaging said bellows end plate, a boss on said upwardly extending portion, a conduit mounted on said boss, said conduit communicating with the interior of said bellows and means to control passage of fluid through said conduit.

CONRAD R. BUCHET.
